UNITED STATES PATENT OFFICE.

MARTIN L. ALLSTOT, OF LAWRENCE, KANSAS.

DRY SEPARATOR AND AMALGAMATOR.

SPECIFICATION forming part of Letters Patent No. 392,978, dated November 20, 1888.

Application filed March 24, 1888. Serial No. 268,375. (No model.)

To all whom it may concern:

Be it known that I, MARTIN L. ALLSTOT, a citizen of the United States, residing at Lawrence, in the county of Douglas and State of Kansas, have invented certain new and useful Improvements in Dry Separators and Amalgamators; and I do hereby declare the following to be a full, clear, and exact description of the invention, such as will enable others skilled in the art to which it appertains to make and use the same.

This invention relates to dry separators and amalgamators for precious metals, and more especially for removing fine particles of gold-dust from the sand or soil with which it is found mixed.

This invention consists in the novel construction and combination of the parts herein-after fully described and claimed.

20 In the drawings, Figure 1 is a side view of the machine. Fig. 2 is a rear end view. Fig. 3 is a vertical longitudinal section. Fig. 4 is a detail plan view of one of the breakers. Fig. 5 is a plan view from below of a portion of the shaking sheep-skin separator and the lever for operating it.

A is the inclosing-case of the machine.

B are the breakers, each of which has four arms, b, triangular in cross-section. The breakers are secured upon the shaft C, journaled in bearings c.

D is a belt-pulley for driving the machine, secured upon one end of shaft C outside the casing, and d is a toothed pinion secured upon the other end of the said shaft.

E is a revoluble fan secured upon shaft e, which is journaled in bearings f in the lower part of the casing, and F is a toothed pinion secured upon the end of shaft e.

40 G is an idle-wheel, which is journaled upon the pin g, secured to the casing by the flange g'. The wheel G gears into the two pinions F and d, and is provided with the crank H, so that the machine may be operated by hand, if desired.

I is an inclined sieve at the top of the machine, upon which the gold-containing dirt is thrown.

1 are stationary plates of copper, which have 50 their upper surfaces amalgamated with quicksilver, and which extend under the breakers,

leaving an exit-opening, i, at the bottom toward the rear.

The sieve I is made of very coarse wire net, and is for the purpose of removing large stones from the dirt. The breakers are for pulverizing and breaking up the lumps of sandy dirt, the particles of which adhere together and inclose considerable gold-dust. The plates I' are secured to the upper parts of the opposite ends of the case, so that the breakers revolve between them. The sharp front edges of the triangular arms of the breakers break and cut up the lumps of dirt and throw the earthy particles and gold against the inclined surfaces of the said plates, which converge and form the outlet i underneath the breakers. The opening i is narrow, so that the dirt does not pass through it until it has been thoroughly broken up by the sharp edges of the triangular arms of the breakers, and repeatedly thrown against the inclined surfaces of the amalgamated plates.

J is an inclined separator formed of sheared sheep-skin having the woolly side uppermost and stretched upon the frame J'. A series of holes, j, is formed in the skin. If desired, some woven woolen material may be stretched upon a backing of leather or other similar material and used in place of the sheared sheep-skin.

K are the guides upon which the frame J' is supported. The separator may be stationary; but it is preferably made to slide. Motion is imparted to the separator J by the lever K', which is pivoted to the casing by the pin k, and is also pivoted to one end of the frame J'.

L is an eccentric secured to the hub of the wheel G, and l is the eccentric-rod, which communicates the motion of the eccentric to the lever K'.

M are copper bars amalgamated with quicksilver, which extend transversely across the sheep-skin separator.

N are the wind-boards which direct the blast of the fan under the separator, and O is a hinged door at the rear of the machine for letting out the material which falls through the perforations in the sheep-skin.

The gold-containing dirt which falls through the sieve is pulverized by the breakers, and the fine gold-dust adheres to the amalgamated

surfaces of plates I'. The remaining particles of gold are caught by the woolly surface of the shaking sheep-skin separator and the amalgamated copper bars which extend across it, and the dirt is blown out at the rear of the machine by the blast of air from the fan.

What I claim is—

1. The combination of the inclosing-case, the revolute breakers, the inclined amalgamated plates secured to the opposite ends of the case and forming a narrow outlet under the breakers, the revolute fan, the inclined separator provided with a woolly surface and with transverse amalgamated bars, and the wind-boards for directing the blast under the said separator.
2. The combination of the inclosing-case, the inclined sieve at the top of the case, the revolute breakers provided with triangular arms, the inclined amalgamated plates secured to the opposite ends of the case and forming a narrow outlet under the breakers, the revolute fan, the inclined separator provided with a woolly surface and with transverse amalgamated bars, and the wind-boards for directing the blast under the said separator.
3. The combination of the inclosing-case, the revolute breakers, the inclined amalgamated plates secured to the opposite ends of the case and forming a narrow outlet under the breakers, the revolute fan, the inclined shaking sheep-skin separator provided with transverse

amalgamated bars and sliding upon guides secured to the casing, and the wind-boards for directing the blast under the said separator.

4. In a dry separator and amalgamator, the combination, with a revolute fan, of the inclined shaking sheep-skin separator provided with perforations and having amalgamated bars extending across its woolly surface, guides for the separator to slide on, and wind-boards for directing the blast underneath the separator.

5. The combination of the inclosing-case, the revolute breakers and fan journaled in the case, the toothed pinions on the ends of the breaker and fan-shafts, the idle-wheel provided with a crank and gearing into the said pinions, the inclined amalgamated plates secured to the opposite ends of the case and forming a narrow outlet under the breakers, the inclined sieve at the top of the machine, the shaking sheep-skin separator, the eccentric, and rod for imparting motion to the said separator, and the wind-boards for directing the blast of the fan under the separator.

In testimony whereof I affix my signature in presence of two witnesses.

MARTIN L. ALLSTOT.
